CONTROL HEAD

Charles Pohl, Los Angeles, Calif., assignor to
Michael P. Hannin, Los Angeles, Calif.

Application April 18, 1930. Serial No. 445,387

10 Claims. (Cl. 285—22)

This invention has to do with a control to be applied to a well casing and it is an object of the invention to provide a practical, effective control head operable to prevent a well from blowing out through the casing.

In the drilling of a deep well there is considerable danger of the well blowing out through the casing. Various packing devices have been proposed and used to prevent the blowing out of wells when the drill pipe or drilling tools are in the casing, while other types of devices are sometimes employed to pack off the upper end of the well casing when there are no tools or drill pipe extending into the well. A blowout preventer or control head is usually applied to the upper end of a well casing to be available to pack off the casing in the event that high pressures are encountered in the well. It is necessary to frequently remove the drilling tools from the casing during the course of drilling a well and it sometimes occurs that high pressures will develop when there are no tools or drill pipe in the casing. In the event that a control head designed to pack between a drill pipe and the casing is mounted on the casing when the tools are withdrawn from the well and high pressures develop, it is necessary to apply a head intended to pack off the casing when there is no drill pipe in the casing. High pressures develop very rapidly and with little warning, so that it frequently occurs that there is insufficient time to replace or exchange one type of head or fitting for another, with the result that the well gets out of control.

It is a general object of my invention to provide a control head to be applied to a well casing that is operable to pack off the casing either when a drill pipe is in the casing or when there is no drill pipe or tools in the casing.

It is another object of the invention to provide a head for a well casing that is operable to pack off the casing either by the weight of a drill pipe or tools extending through the casing or by applying an upward pull to the drill pipe.

Another object of the invention is to provide a control head of the character mentioned that may be operated to pack off the casing when there is no drill pipe in the casing by clamping downwardly on a removable plug arranged in the head or by pulling upwardly on the plug.

It is a further object of the invention to provide a control head of the character mentioned that may be quickly and easily applied to a casing and which does not interfere with normal drilling operations when in position on the casing.

Other objects and features of my invention will be best and more fully understood from the following detailed description of a typical form and application of the invention, throughout which description reference is had to the accompanying drawing, in which:

Fig. 1 is a vertical detailed sectional view of the control head provided by this invention illustrating a drill pipe extending through it. Fig. 2 is a view similar to Fig. 1 illustrating the plug provided by the invention in operating position in the head. Fig. 3 is a vertical detailed sectional view of the head being a view taken as indicated by line 3—3 on Fig. 1. Fig. 4 is a vertical detailed sectional view of the head being a view taken as indicated by line 4—4 on Fig. 2. Fig. 5 is a top or plan view of the head taken as indicated by line 5—5 on Fig. 2. Fig. 6 is a transverse detailed sectional view taken as indicated by line 6—6 on Fig. 1, and Fig. 7 is a vertical detailed sectional view of the packing assembly embodied in the invention being a view taken substantially as indicated by line 7—7 on Fig. 6.

The device provided by this invention includes, generally, a body 10 adapted to be applied to a well casing, packing means 11 adapted to be arranged in the body 10, means 12 for locking the packing 11 in position or for operating the packing, and a plug 13 adapted to be employed in connection with the device when the device is used to pack off a well casing in which there is no drill pipe, or the like.

The body 10 is adapted to be applied to the upper end of a well casing. The body 10 is tubular having a central longitudinal opening 14 for passing a drill pipe P, or the like, and for carrying the packing means 11. In practice any suitable means may be provided for connecting the body 10 to a well casing. In the particular form of the invention illustrated in the drawing the lower portion 16 of the body is externally and internally screw threaded so that it is adapted to be screw threaded onto a coupling or other suitable connecting part on a casing. Openings or ports 17 may be provided in the walls of the body 10 to receive discharge pipes or conduits 18 for discharging gas and fluid when the head is in operation. An upwardly and outwardly tapered annular shoulder 19 is provided in the walls of the opening 14 above the ports 17. The portion of the opening 14 above the shoulder 19 is formed to slidably receive the packing means 11 and is preferably of the same diameter throughout its length.

The packing means 11 is an annular construction or assembly adapted to operate in the opening 14 of the body to pack between the drill pipe P and the body 10. The packing means 11 is adapted to be removably arranged in the upper portion of the opening 14 above the tapered shoulder 19. The packing means 11 may include a body of packing 20 arranged between rings 21 and 22. The packing 20 is preferably compressible and resilient and may be formed of rubber, rubber composition, or the like. The packing ring 22, which is at the lower end of the body of packing 20, is formed to seat against the tapered

- shoulder 19 and its exterior is tapered to fit the shoulder 19. The packing ring 21 at the upper end of the body of packing 20 is formed to slidably fit the upper portion of the opening 14 of the body.
- 5 Grooves 23 may be provided in the ends of the rings 21 and 22 engaging the packing 20 and tongues 24 may be provided on the packing to fit into the grooves 23. The rings 21 and 22 are divided or split longitudinally at diametrically opposite points, while the packing 20 is split longitudinally at one side along a line registering with the lines of separation of the rings 21 and 22 so that the packing assembly 11 may be easily arranged or sprung over the drill pipe P and lowered 10 into the opening 14 without disturbing the drill pipe. In practice it is desirable to join or connect the several parts of the packing means 11 so that it is in the form of a unitary assembly to be readily handled. The rings 21 and 22 may be 15 connected by means of tie members 26 extending between the rings and passing through openings 27 in the body of packing 20. The tie members 26 may be in the form of screws having their lower ends screw threaded into the lower packing ring 22 and having their upper ends operable in openings 28 in the upper ring 21. The upper end of the upper packing ring 21 is preferably made flat and is adapted to be engaged by or to support a drill pipe coupling C or other projecting part on 20 the drill pipe to actuate the packing 20.
- The means 12 is provided for locking the packing means 11 in operating position in the body 10 and may be operated to compress the packing 20 into sealing position. The means 12 includes 25 a collar 29 screw threaded on the upper portion of the body 10. The collar 29 may be removably threaded on the body and handles 30 may be provided on the collar. A sectional compression member 31 may be provided on the collar 29 to engage the packing ring 22 to lock the packing means in the body or for actuating the packing means. The sectional packing member 31 includes 30 two like sections 32 pivotally mounted on the upper side of the collar 29. The sections 32 are arcuate and may be substantially semi-circular in their general configuration. Adjacent ends of the sections 32 may be pivoted or hinged to the collar 29 by means of hinges or bolts 33. The pivoted ends of the sections 32 are curved 35 and formed so that the sections are adapted to be swung to out positions such as illustrated in the broken lines in Fig. 5 of the drawing so that the packing assembly 11 may be readily lowered into the opening 14. The inner edges of the sections 32 are provided with curved or substantially semi-circular recesses 36 which are adapted to form a substantial round opening for passing the drill pipe P when in the in or closed position. The opening formed by the recesses 36 is preferably 40 sufficiently large to freely pass a drill pipe coupling C, or the like, so that the coupling may engage the upper side of the packing ring 22. In accordance with the invention means may be provided for releasably holding the sections 32 in the in or closed position. In the drawing I have shown bolts or pins 37 adapted to be arranged through openings in the outer or free ends of the sections 32 and adapted to seat in openings 38 in the collar 29 to retain the sections in operating positions. The sections 32 are formed so 45 that they are adapted to be brought into engagement with the upper end of the packing ring 21 to lock the packing assembly 11 in the body when the collar 29 is threaded downwardly on the body. The sections 32 are provided with downwardly 50 projecting flanges 39 at their peripheries or edges. Inwardly projecting flanges 40 are provided at the lower ends of the flanges 39 to seat into an annular recess or groove 41 in the collar 29. The flanges 40 and the groove 41 are formed and related so that the flanges 40 are adapted to be freely swung into the groove and tightly fit the groove when the sections 32 are in the in or operating positions.
- The plug 13 is intended to be employed when it is desired to pack off or close a well casing when there is no drill pipe or the like extending through the casing. The plug 13 is an elongated cylindrical part adapted to extend into the head 10. The plug 13 is an elongated cylindrical part adapted to extend through the packing assembly 11. The plug 13 may be about the same size as the drill pipe. The plug 13 is made sufficiently long to project downwardly from the lower end of the packing assembly 11 and to project above the upper end of the head when in operating position in the device. The plug 13 is provided with an annular radial flange 45 adapted to seat against the upper side of the ring 21 and adapted to be engaged by the lower sides of the sections 32. The flange 45 is preferably of substantially the same diameter as the ring 22 so that it is engaged by the sections 32 when the collar 29 is operated to compress the packing 20. A lower radial flange 46 is provided on the plug 14 to be 105 at the lower side of the packing ring 22. The flange 46 is adapted to engage the packing ring 22 to compress the packing when an upward pull is exerted on the plug when the sections 32 of the locking means are in operating position. In accordance with the preferred form of the invention means is provided in connection with the plug 42 for carrying and suspending the plug and for applying an upward pull to the plug when desired. In the form of the invention illustrated 110 a bail or ring 47 is provided at the upper end of the plug 13 for receiving a line, or the like, for suspending and handling the plug. The plug 13 is adapted to be suspended within a well derrick to be in position to be lowered into the head 10 when it is desired to pack off a well casing when the drilling or operating tools are withdrawn from the well.
- Normal drilling operations may be performed with the body 20 of the head applied to the upper end of the casing and the sections 32 may be swung to the out positions shown in broken lines in Fig. 5 to permit full operation of tools through the head and well casing. When there are indications that high pressures have been 115 encountered in a well and a blow out is likely to occur while a drill pipe P, or the like, is in the well casing and it is desired to pack between the well casing and the drill pipe, the packing assembly 11 may be assembled or arranged around the drill pipe and lowered into the opening 14 of the head. The sections 32 of the locking means may then be swung into their operating positions and the collar 29 may be screwed down on the body to lock the packing means in the operating position. The packing may then be operated 120 into tight sealing engagement with the drill pipe P and the walls of the body opening 14 either by allowing the drill pipe P to lower so that a drill pipe coupling C or other projecting part of the 125 pipe engages the packing ring 22 to compress the packing 20, or an upward pull may be applied to the drill pipe P so that a drill pipe coupling 50 below the packing means 11 is brought into engagement with the lower packing ring 21 to com- 130
- 135
- 140
- 145
- 150

press the packing. If desired or necessary, the collar 29 may be screwed onto the body 10 to compress the packing through the locking sections 32.

When it is desired to pack off in a well casing 5 when there is no drill pipe in the casing the plug 13 may be swung to a position above the control head and the packing assembly 11 may be arranged around the plug between the flanges 45 and 46 and the plug lowered into the opening 14.

- 10 The sections 32 of the locking means may then be swung to the in position and the collar 29 screwed downwardly on the body to operate the sections 32 into locking positions. Either a downward or upward force may be applied to the plug 15 13 to operate the packing 20 into tight sealing engagement with the plug and the body 10.

It is to be noted that the invention provides a control head that is operable to pack off a well casing when there is drill pipe in the casing as 20 well as when there is no drill pipe or other tools extending through the casing. It is to be further noted that the invention provides a control head that is operable to effectively pack off a well casing when drill pipe is in the casing 25 which is not of sufficient weight to properly actuate the packing. The sections 32 of the locking means are formed and mounted on the collar 29 so that they may be employed to operate the packing if desired or necessary and permit a drill 30 pipe coupling or other projecting part on a drill pipe to engage the packing means for operating the packing.

Having described only a typical preferred form of my invention, I do not wish to limit myself to the specific details set forth, but wish to reserve to myself any changes or variations that may appear to those skilled in the art or fall within the scope of the following claims:

Having described my invention, I claim:

40 1. A casing head of the character described including, a body adapted to be applied to the casing and having an opening, packing means in the opening operable by compression, and means for locking the packing means in the body, including a collar screw threaded to the body, and pivoted sections on the collar adapted to engage the upper end of the packing means, the sections providing an opening to pass a projecting part on an object extending through the body.

50 2. A casing head of the character described including, a body adapted to be applied to the casing and having an opening, packing means in the opening operable by compression, and means for locking the packing means in the body, including a collar screw threaded to the body, pivoted sections on the collar adapted to engage the upper end of the packing means, and flanges on the sections to seat in a groove in the collar when in the engaging position.

60 3. A casing head including, a body adapted to be applied to the casing and having an opening, compressible packing means in the body opening for sealing about an object extending through the body, a plug adapted to be arranged through the packing means to be sealed about thereby, a projecting part on the plug for engaging the upper end of the packing means, and means adapted to engage said part and compress the packing means, said means including a collar threaded on the body, and pivoted sections on the collar adapted to engage said part.

4. A casing head including a body to be applied to the upper end of a well casing, packing means in the body to pack off about drill pipe

or the like, extending into the well, a plug adapted to be arranged through the packing means when the pipe is not present, a projecting part on the plug for engaging the upper end of the packing means, and a pivoted section carried by the body operable to engage the upper end of the packing means when the pipe is present and operable to engage the said projecting part when the plug is in the packing means.

5. A casing head including a body to be applied to the upper end of a well casing, packing means in the body to pack off about drill pipe or the like, extending into the well, a plug adapted to be arranged through the packing means when the pipe is not present, a projecting part on the plug for engaging the upper end of the packing means, a collar threaded on the body, and a horizontally pivotable section on the collar adapted to engage either the upper end of the packing means or the said projecting part.

6. A casing head of the character described including, a body to be applied to the casing and having an opening through it, packing means to be arranged in the opening, and means for locking the packing means in the body including a collar threaded on the body and horizontally pivotable sections at the upper end of the collar to engage the packing means.

7. A casing head of the character described including, a body adapted to be applied to the casing and having an opening, an annular packing assembly in the body and adapted to seal about a drill pipe, or the like, a plug adapted to be inserted in the packing assembly to close it when the pipe is removed, and means for locking the packing means in the body, including a shiftable member on the body shiftable to engage an end of the packing assembly when the pipe is present and adapted to engage the plug to lock the packing assembly in the body when the plug is in the assembly.

8. In combination with a casing head having a body with an opening, packing means in the opening having an opening for passing a drill pipe, a plug of substantially the same extent as the body adapted to be arranged through the opening in the packing means to completely fill and plug the opening, a part on the plug adapted to engage the upper end of the packing means a shiftable member carried by the body operable to a position where it engages said part to lock the plug in the packing opening.

9. In combination with a casing head having a body with an opening, packing means in the opening having an opening for passing a drill pipe, a plug adapted to be arranged through the opening in the packing means to completely fill and plug the opening, a part on the plug adapted to engage the upper end of the packing means, a part on the plug adapted to engage the lower end of the packing means, and a shiftable member on the body operable to engage one of said parts to hold the plug in the packing opening.

10. A casing head including, a body to be applied to the upper end of the casing, an annular packing assembly in the body to seal about pipe, a manually portable plug for arrangement in the packing assembly when the pipe is removed, and means adapted to act through the plug for compressing the packing assembly to seal with the plug and adapted to directly compress the packing assembly when the plug is not present.
